(57) **CLAIM**

The ornamental design for a fly swatter as shown and described.

DESCRIPTION

FIG. 1 is a front elevation view of a fly swatter showing my new design, a rear view being a mirror image thereof;
FIG. 2 is a front isometric view thereof;
FIG. 3 is a left side view thereof, a right side view being a mirror image thereof;
FIG. 4 is a top plan view thereof;
FIG. 5 is a bottom plan view thereof; and,
FIG. 6 is a front elevation view thereof, showing a modified form of the design.
